US0D1018818S

(12) **United States Design Patent** (10) Patent No.: **US D1,018,818 S**
(45) Date of Patent: ** Mar. 19, 2024

(54) **IONIZING BAR**

(71) Applicant: **Illinois Tool Works Inc.**, Glenview, IL (US)

(72) Inventors: **Steven Bernard Heymann**, Los Gatos, CA (US); **Aleksey Klochkov**, San Francisco, CA (US); **Juan Guerrero**, Berkeley, CA (US)

(73) Assignee: **Illinois Tool Works Inc.**, Glenview, IL (US)

(**) Term: **15 Years**

(21) Appl. No.: **29/787,261**

(22) Filed: **Jun. 4, 2021**

(51) LOC (14) Cl. **23-04**

(52) U.S. Cl.

USPC **D23/366**

(57) **CLAIM**

The ornamental design for an ionizing bar, as shown and described.

DESCRIPTION

FIG. 1 is a front perspective view of an ionizing bar;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a bottom plan view thereof; and,

FIG. 7 is a top plan view thereof.

The broken lines in the drawings illustrate portions of the ionizing bar that form no part of the claimed design.
